SPRING ROLLER CONSTRUCTION

Frank May, Beechurst, N. Y.

Application October 26, 1936, Serial No. 107,689

1 Claim. (Cl. 156—39)

The present invention relates to roller screens adapted to form an openable closure for windows and the like.

The general object of the invention is to provide a roller screen particularly adapted for convenient installation on the outside of a window so as thereby to obviate the necessity for frequent opening of the roller screen to permit opening of the window.

Another object resides in the provision of an improved spring roller in conjunction with a roller window screen, the novel arrangement of the roller affording convenient means for readily adjusting the tension of the torsional spring thereof without requiring the removal of the roller to accomplish the mentioned setting.

A further object of the invention is to provide an improved construction of a window screen and spring roller for same comprising certain features of novelty which render the device readily adaptable to windows of various sizes, thereby permitting the manufacture of a standard size of window screen which may be installed on windows varying in dimensions with a minimum of alteration to the screen and operating mechanism thereof.

The invention will be fully and comprehensively understood from a consideration of the following detailed description when read in connection with the accompanying drawing which forms part of the application.

In the drawing:

Fig. 1 is a perspective view of a typical window installation including the roller screen of the invention.

Fig. 2 is a vertical sectional view thru a typical window equipped with the roller screen of the invention.

Fig. 3 is a detail longitudinal sectional view thru the casing of the device illustrating the spring roller thereof, parts being shown in central section.

Fig. 4 is an enlarged end elevational view of the spring roller shown in Fig. 3; and

Fig. 5 is a fragmentary elevational view of one end of the roller shown in Fig. 3.

Reference is now had to the accompanying drawing for a more detailed description thereof, wherein the numeral 6 indicates a suitable box-like casing adapted for attachment preferably to the outside of a window frame, being secured thereto as by the screws 7. The casing 6 is open at the side adjacent to the window to which it is attached, the bottom of the casing being flanged 55 at 8 to present a resilient edge for contact with

the roller screen. Within the casing 6 is provided a spring roller 9 rotatably mounted therein as illustrated in Fig. 3. The roller 9, being spring-actuated, is adapted to receive the entire length of screen fabric 10, the latter being supported 5 upon the periphery of the roller 9.

To the respective sides of the window frame is affixed suitable guide channels 11, the same being preferably fabricated of sheet material bent upon itself to form a channel structure into which the 10 lateral edges of the screen fabric 10 are slidably disposed. It is to be noted here that the screen fabric 10 being wound upon the spring roller 9 increases in diameter. To compensate for this action a guide roller 12 is employed, the same being 15 rotatably mounted on the ends of the casing 6 and disposed tangentially to the guide channels 11 so as to guide the screen fabric 10 from the spring roller 9 in proper alignment with the channels 11. 20

The free edge of the screen fabric 10 is reinforced by a rigid strip 13 to which are secured suitable spring latches 14 at each end thereof. The spring roller 9 imparts a constant tension to the screen fabric 10 so as to permit convenient 25 opening of the screen as well as to tension the span of the screen fabric 10 in position over the window to prevent distortion of same. The screen fabric 10 in closed position over the window is retained in this position by the engagement 30 of the spring catches 14 with complementary latch plates 15 mounted on the guide channels 11. Simultaneously release of the catches 14 will thus 35 permit rapid opening of the screen 10, the same being actuated by the spring roller 9 to wind the screen thereon.

To facilitate adjustment of the tension of the spring roller 9 same embodies novel means illustrated in Fig. 3. The spring roller 9 is formed at one end in an axial bore 16 in which is housed 40 a torsional spring 17, the latter being retained on a rotatable rod 18 journaled within the roller 9. The free ends of the spring 17 are affixed respectively to the rod 18 and the roller 9 so as to impart a rotation to the latter. The outer end 45 of the rod 18 is equipped with a cylinder 19 by which the rod 18 is journaled in a plate 20 secured to the end of the roller 9. A series of notches 22 are formed in the periphery of the cylinder 19, the notches constituting a ratchet wheel. The 50 cylinder 19 is also formed with an axially extending lug 21 for engagement with a suitable socket 23 mounted on the casing 6.

The structure of the roller 9 thus far described provides for imparting a rotation to the roller by 55

the torsional spring 17. To permit adjustment of the spring 17 to the desired tension a pawl 24 is provided, the same being swingably mounted on a stud 25 secured to the plate 20. The pawl 24 is arranged to have its free end engage in one of the series of notches 22 so as to lock the roller 9 against rotation relative to the rod 18. This locking is employed only during adjustment of the spring 17, which adjustment is effected by 10 pulling down the screen 10, thus winding the spring 17 whence the pawl 24 is released to drop into one of the notches 22. Further tensioning of the spring 17 may be effected by disengaging the roller 9 from its sockets and thereafter manually 15 winding up the screen fabric thereon. The roller being replaced in its sockets may be further tensioned by again drawing down the screen 10 until the desired tension of the spring 17 is had.

It will be apparent that the pawl 24 functions 20 only during adjustment of the spring 17 and that in actual use the spring 17 is free to impart a rotation to the roller 9, the pawl 24 being held in inactive position as shown in phantom outline in Fig. 4. The pawl 24 is formed with a laterally extending lug 26, the same presenting an inclined surface 27 functioning to retract the pawl 24 to ineffective position. Rotatably mounted on the end of the roller 9 is a cylindrical ferrule 28 having a slot 29 therein in which the lug 26 is disposed. It will be apparent that by rotation of the ferrule 28 on the roller 9 that an end of the slot 29 engages the inclined surface 27 of the lug 26 thereby camming the pawl 24 out of engagement with the notch 22 and into ineffective position, the 30 ferrule 28 being formed with a series of ears 30 for convenience in rotating the ferrule 28.

In the opposite end of the roller 9 is formed an axial bore 31 in which is slidably disposed a stud shaft 32, the latter being backed by a spring 33. 35 The stud shaft 32 has a slot 34 formed in its periphery in which slot is disposed a pin 35 se-

cured to the roller 9 and adapted to engage the ends of the slot 34 to limit the endwise movement of the stud 32. The free end of the stud shaft 32 is reduced to form a trunnion 36, the same being engaged in a suitable socket 37 secured to an 5 end of the casing 6. The arrangement of the stud shaft 32 as described permits the roller 9 to be accommodated in various sizes of windows in that the stud shaft 32 being axially extensible 10 effects the lengthening of the roller 9 to fit the window, the position of the shaft 32 being retained by the pressure of the spring 33. It will also be apparent that the resilient mounting of the shaft 32 facilitates adjustment of the tension 15 of spring 17 as described by permitting convenient withdrawal of the lug 21 axially from its socket 23 as well as to function during the entire removal of the roller 9 from the casing 6.

It is to be understood that this improvement is 20 capable of extended application and is not confined to the exact showing of the drawing nor to the precise construction described and, therefore, such changes and modifications may be made therein as do not affect the spirit of the invention 25 nor exceed the scope thereof as expressed in the appended claim.

What is claimed as new is:

A spring roller construction adapted for mounting 30 on a window frame and to receive a screen fabric thereon, comprising, a roller, an interiorly arranged torsional spring for rotating said roller, a ratchet wheel secured to said spring, a pawl associated with said wheel to lock the same upon adjustment of said spring in one direction, and a ferrule having a pawl operating slot for receiving 35 an end of said pawl and rotatably mounted on said roller whereby said slot functions to cam said pawl out of engagement with said wheel upon rotation of said ferrule relative to said roller.
